MAN PUPPET

Juanita A. Casey and Kathleen L. Johnson, Del City,
Okla. (both of 7055 Lenox, Apt. 5, Van Nuys, Calif.
91405)

Filed Jan. 28, 1975, Ser. No. 544,929

Term of patent 7 years

Int. Cl. D21—01

U.S. Cl. D34—4 R

FIG. 1 is a front perspective view showing the characteristics of the facial portion of the head and generally the front of a man puppet showing our new design.

FIG. 2 is a rear perspective view showing the characteristics of the back portion of the head and generally the back of the man puppet design of FIG. 1.

We claim:

The ornamental design for a man puppet, substantially as shown and described.
